UNITED STATES PATENT OFFICE.

HENRY E. HENRICKS, OF BEAVER, PENNSYLVANIA, ASSIGNOR TO UNITED STATES SANITARY MANUFACTURING COMPANY, OF PITTSBURGH, PENNSYLVANIA, A CORPORATION OF PENNSYLVANIA.

MATERIAL HANDLING APPARATUS.

Application filed May 17, 1924. Serial No. 713,951.

The present invention relates broadly to material handling apparatus, and more particularly to an apparatus of this character especially adapted for making sand molds.

In the art to which this invention relates, it is desirable to supply sand to mold flasks under such conditions that it is compacted to the desired extent without necessitating the use of ramming or packing devices. As the mold flasks are frequently arranged at different angles, and frequently have undercut sides or overhanging edges, it will be apparent that it is necessary to provide projecting means for the sand which is capable of substantially universal adjustment.

I have found that with any rotating projector, the sand tends to leave the same along the line of a tangent which is perpendicular to a horizontal plane passing through the axis, or one of the axes, of rotation of the projector. In order, therefore, to properly compact sand along the edges of an undercut mold, it is necessary to provide a projector capable of such adjustment that the tangential line followed by the material may assume any desired angularity with respect to a given horizontal plane. My invention also has for one of its objects the provision of a projector possessing these characteristics.

In the accompanying drawings, there is shown, for purposes of illustration only, one embodiment of the present invention, it being understood that the drawings do not define the limits of the invention, as changes may be made in the construction and operation therein disclosed, without departing from the spirit of the invention or scope of my broader claims.

In the drawings:

Figure 1 is a side elevation, partly broken away and partly in section, of one embodiment of my invention;

Figure 2 is an end elevation, partly broken away, of the projector end of the apparatus illustrated in Figure 1;

Figure 3 is a vertical sectional view on the line III-III of Figure 2, and

Figure 4 is a detail view, on an enlarged scale, of the projector driving and adjusting mechanism.

In carrying out the present invention, there may be provided a fixed base 2 adapted to carry a standard 3 which may be rotatably mounted thereon in any desired manner. This standard at its upper end may carry a material supply means in the form of a hopper 4 to which material may be delivered in any convenient or usual manner. This hopper may be provided with a shaking table or screen 5 adapted to sift the material as supplied, the finer grades passing through the hopper to a rotating feed device 6 which delivers the material through a spout 7 to a conveyor 8.

Mounted on the standard 3 is a motor 9 having a driving connection 10 with a pulley 11 mounted on one end of a shaft 12. This shaft, at an intermediate portion, carries a worm 13 meshing with a worm wheel 14 splined to a shaft 15. This shaft at one end is provided with a bevel gear 16 meshing with a similar gear 17 on one end of a shaft carrying a conveyor supporting roller 18. This shaft is journaled in a suitable frame 19, the opposite end of which carries a second roller 20.

Also driven by the shaft 15 is a sprocket 21 adapted to drive the shaft 22 which carries the feed device 6. This shaft, in turn, is provided with a pulley 23 for a belt 24 serving as a driving means for the eccentric 25 which reciprocates the table or screen 5. By reason of this construction, it will be apparent that the screen, the feed device and the conveyor are driven simultaneously from a common motor, irrespective of the position to which the standard 3 is turned on its support.

Cooperating with the standard 3 is a crane 26 which is movable toward and away from the support on rails 27. The crane 26, which may conveniently be of any well known bridge type, carries a buggy 28 which is movable at substantially right angles to the direction of travel of the crane by the

provision of tracks 29. The buggy has secured thereto and suspended therefrom a C frame 30, the lower end of which terminates under substantially the center of the buggy. This frame carries a supporting bracket 31 on which is rotatably mounted a pair of supports 32 for the outer end of the conveyor frame 19. The C frame 30 is preferably provided with a window or opening 33, as clearly shown in Figure 2, to permit the passage of the conveyor therethrough.

With this construction, it will be apparent that irrespective of the direction of movement either of the crane 26 or of the buggy 28, the distance between the bracket 31 and the standard 3 will be varied. In order to permit this movement, it is necessary to so mount the conveyor frame 19 that it may slide through the standard 3. This may be accomplished by providing transversely extending supporting rollers 34 in the standard extending through slots 35 in the conveyor frame 19 and permitting it to move as required. It will be apparent that at such times the shaft 15 moves endwise through the worm wheel 14 and the driving means for the sprocket 21, thereby maintaining the desired driving relationship at all times, irrespective of the position of the conveyor. Movement of the buggy 28 on the tracks 29 is permitted by reason of the rotatable mounting of the standard 3 and of the supports 32.

Rotatably carried on the C frame 30 on suitable bearings 36 is a projector frame 37. This projector frame is preferably so constructed that with the parts in the position illustrated in Figure 1, the C frame and the projector frame will be substantially balanced with the center of gravity on the axis of rotation of the projector frame about the bearings 36. The projector frame itself is also preferably balanced about its axis of rotation by mounting a driving motor 38 on one end of the frame and the projecting apparatus per se on the opposite end of the frame, as will be hereinafter more fully described.

Carried by the frame 37 is a second conveyor 39 adapted to be driven at any desired speed, but preferably at a speed substantially equal to that of the conveyor 8, by the motor 38 and the intermediate shaft 40 with its gear train, as clearly shown in Figure 1. Mounted above the conveyor 39 is a hopper 41 adapted to direct the sand from the conveyor 8 to conveyor 39, which in turn discharges into a hopper 42. The hopper 42 is mounted to discharge directly on to an endless projector 43 preferably in the form of a flexible V belt, as clearly shown in Figure 3. This projector is supported to travel around suitable guide rollers or pulleys, as well understood in the art, and car-

ries a plurality of projecting paddles 44. There are preferably but two of these paddles provided, as indicated in Figure 2. The projector is substantially completely enclosed in a suitable housing 45 from the upper portion of which projects a pair of flanges or guides 46, these guides being spaced a distance to permit the travel of the paddles 44 therebetween, but to prevent the material from falling from the projector.

The projector is adapted to be driven at comparatively high speed by the motor 38, which is connected by means of shaft 47 and flexible coupling 48 with one of the projector driving pulleys. By reason of this construction, it will be understood that the travel of the projector causes material supplied by the hopper 42 to gradually pile up ahead of one of the projector paddles. Due to the high speed of travel of the projector, this material will be carried to the left hand end of the housing, as viewed in Figure 2, where it is adapted to be discharged through the outlet 49. As I have before pointed out, this discharge usually follows a tangential line which is substantially perpendicular to a horizontal plane which includes the axis, or at least one of the axes, of rotation of the projector. Thus with the projector positioned as in Figure 2, the material will be discharged in substantially the direction of the dotted line *a*, which line is substantially perpendicular to the dotted line *A* passing through the axes of rotation of the pulleys which carry the projector. It may happen, however, that it is desired to fill a mold flask *F* having substantially the shape illustrated in this figure. In order to properly compact the sand along the sides of the flask, it is necessary to produce a line of discharge parallel to the chain line *b*. To accomplish this, the entire projector must be so adjusted that the plane containing the axes of the pulleys before referred to is brought into substantially the position of the chain line *B*. This is easily accomplished with the construction herein provided, as the projector housing is adapted to be angularly adjusted about the axis of rotation of the projector driving means. This is accomplished by providing a segmental gear 50 on one end of the housing meshing with a spur gear 51 on one end of a shaft 52 journaled in suitable bearings 53 on the frame 37. This shaft is driven by a worm wheel 54 meshing with a worm 55 on a shaft 56 carrying at one end a spur gear 57. This spur gear in turn meshes with a similar gear 58 on a shaft 59 parallel to and overlying a portion of the shaft 56. The shaft 59 at its opposite end carries a bevel gear 60 adapted to be driven in one direction by a bevel gear 61 and in the opposite direction by a bevel gear 62. The bevel gears 61 and 62 are loosely mounted on the shaft 47, but

are adapted to be operatively connected to this shaft at will, through the medium of a clutch member, 63, longitudinally shiftable therebetween. This construction is such that the shaft, 52, may be turned in one direction for lowering the discharge end of the projector, or, in the opposite direction, for raising the same. In this manner, the projector may be adjusted so that the material is discharged therefrom at high speed and in a direction such that the most efficient filling and packing of the mold flask is insured. By reason of the provision of the comparatively few number of projector paddles, the sand is discharged in successive batches at high velocity, insuring a more thorough packing.

Certain advantages of the present invention arise from the provision of an apparatus having substantially universal adjustment, it being possible to move the frame bodily laterally or longitudinally, and then rotate the projector frame, 37, to any desired position with respect thereto. Thereafter, the angularity of the projector itself may be adjusted to insure proper packing of the sand.

Other advantages of the invention arise from the construction of the projector and the means for adjusting the same.

Still further advantages arise from the frame for supporting the projector, and from the construction of the projector frame itself which permits the entire structure to be substantially balanced.

I claim:

1. In a mold making apparatus, a frame adapted to be bodily moved longitudinally or transversely, means for supplying sand to said frame, and a projector pivotally mounted on said frame receiving sand from said means and delivering it to a mold, substantially as described.

2. In a mold making apparatus, a frame adapted to be bodily moved longitudinally or transversely, means for supplying sand to said frame, and an angularly adjustable positively driven projector on said frame receiving sand from said means and delivering it to a mold, substantially as described.

3. In a mold making apparatus, a frame adapted to be bodily moved longitudinally or transversely, means for supplying sand to said frame, an endless projector on said frame receiving sand from said means and delivering it to a mold, and means for angularly adjusting said projector for changing the angle of discharge of said projector, substantially as described.

4. In a mold making apparatus, a frame adapted to be bodily moved longitudinally or transversely, means for supplying sand to said frame, an endless projector on said frame receiving sand from said means and

delivering it to a mold, and means for varying the angle of discharge of said projector by raising or lowering the discharge end of said projector, substantially as described.

5. In a mold making apparatus, a frame adapted to be bodily moved longitudinally or transversely, means for supplying sand to said frame, and a projector on said frame receiving sand from said means and delivering it to a mold, said projector being angularly adjustable to different positions on said frame, substantially as described.

6. In a mold making apparatus, oppositely extending tracks, a crane bodily movable on said tracks in either of two directions at substantially right angles to each other, a frame suspended from said crane, means for supplying sand to said frame, and a projector on said frame receiving sand from said means and delivering it to a mold, substantially as described.

7. In a mold making apparatus, a frame adapted to be bodily moved longitudinally or transversely, means for supplying sand to said frame, a projector on said frame receiving sand from said means and delivering it to a mold, a motor on said frame for driving said projector, and means adapted to be operatively connected to said motor for adjusting the angularity of discharge of said projector, substantially as described.

8. In a sand handling apparatus for molds, a crane, an offset open sided frame suspended from said crane, and a projector frame carried by said offset frame and counterbalancing the same, substantially as described.

9. In a sand handling apparatus for molds, a crane, an offset open sided frame suspended from said crane, and a projector frame rotatably carried by said offset frame and counterbalancing the same, substantially as described.

10. In a sand handling apparatus for molds, a crane, an offset frame suspended from said crane, and a substantially balanced projector frame movably carried by said offset frame and counterbalancing the same, substantially as described.

11. A projector for mold making apparatus, comprising an endless conveyor, at least two pulleys around which said conveyor travels, and means for adjusting said projector whereby a tangent perpendicular to a horizontal plane passing through the axis of rotation of at least one of said pulleys may assume different angular relationships to the plane of support of a mold to be filled, substantially as described.

12. A projector for mold making apparatus, comprising a housing having a pivotal mounting, an endless projecting conveyor enclosed within said housing, and means for angularly adjusting said housing and said

conveyor about said mounting for varying the angle of discharge of said conveyor, substantially as described.

13. In a mold making apparatus, a supply means, a frame movable relatively to said means, an endless projector on said frame, conveying means for delivering sand from said means to said projector, and means for adjusting the angularity of said projector for varying the angularity of discharge of said projector, substantially as described.

14. In a mold making apparatus, a supply means, a frame movable relatively to said means, a projector adjustable vertically to different angular positions and horizontally on said frame, and conveying means for delivering sand from said means to said projector, substantially as described.

15. In a material handling apparatus, a standard mounted for rotation, a conveyor having one end slidably supported by said standard, means carried by said standard for delivering material to said conveyor, a frame movable relatively to said standard, a rotatable support on said frame for the opposite end of said conveyor, and a projector on said frame adapted to receive material from said conveyor and discharge the same, substantially as described.

16. In a material handling apparatus, a standard mounted for rotation, a conveyor having one end slidably supported by said standard, means carried by said standard for delivering material to said conveyor, a frame movable in a plurality of different directions relatively to said standard, a rotatable support on said frame for the opposite end of said conveyor, and a projector on said frame adapted to receive material from said conveyor and discharge the same, substantially as described.

17. In a material handling apparatus, a standard mounted for rotation, a conveyor having one end slidably supported by said standard, means carried by said standard for delivering material to said conveyor, a frame movable relatively to said standard, a rotatable support on said frame for the opposite end of said conveyor, and a projector on said frame adapted to receive material from said conveyor and discharge the same, said projector being rotatably supported by said frame, substantially as described.

18. In a material handling apparatus, a standard mounted for rotation, a conveyor having one end slidably supported by said standard, means carried by said standard for delivering material to said conveyor, a frame movable relatively to said standard, a rotatable support on said frame for the opposite end of said conveyor, and a projector on said frame adapted to receive material from said conveyor and discharge the same, said projector being adjustably mounted on said frame, substantially as described.

19. In a material handling apparatus, a standard mounted for rotation, a conveyor having one end slidably supported by said standard means carried by said standard for delivering material to said conveyor, a frame movable relatively to said standard, a rotatable support on said frame for the opposite end of said conveyor, and an endless projector on said frame adapted to receive material from said conveyor and discharge the same, substantially as described.

20. In a material handling apparatus, a standard mounted for rotation, a conveyor having one end slidably supported by said standard, means carried by said standard for delivering material to said conveyor, a frame movable in a plurality of different directions relatively to said standard, a rotatable support on said frame for the opposite end of said conveyor, and an endless projector on said frame adapted to receive material from said conveyor and discharge the same, substantially as described.

21. In a material handling apparatus, a standard mounted for rotation, a conveyor having one end slidably supported by said standard, means carried by said standard for delivering material to said conveyor, a frame movable relatively to said standard, a rotatable support on said frame for the opposite end of said conveyor, and an endless projector on said frame adapted to receive material from said conveyor and discharge the same, said projector being rotatably supported by said frame, substantially as described.

22. In a material handling apparatus, a standard mounted for rotation, a conveyor having one end slidably supported by said standard, means carried by said standard for delivering material to said conveyor, a frame movable relatively to said standard, a rotatable support on said frame for the opposite end of said conveyor, and an endless projector on said frame adapted to receive material from said conveyor and discharge the same, said projector being adjustably mounted on said frame, substantially as described.

23. Projecting means for sand handling apparatus, comprising a projecting conveyor having an upper run normally extending in a substantially horizontal direction, means for adjusting the angularity of said run relatively to the horizontal, and a housing enclosing said conveyor and provided with a downwardly directed discharge opening for said conveyor, substantially as described.

24. Projecting means for sand handling apparatus, comprising spaced projector mountings, a projecting conveyor carried by said mountings and normally extending substantially horizontally, means for adjusting the angularity of said conveyor, and a housing enclosing said conveyor and provided with a downwardly directed discharge open-

ing for said conveyor, substantially as described.

25. In a sand handling apparatus, a movable overhead support, an offset open sided frame depending from said support, and a counterbalanced projector frame extending through the open side of said frame, said projector frame having a pivotal mounting on said offset frame, substantially as described.

26. In a sand handling apparatus, a mov-

able overhead support, an offset open sided frame carried by said support, and a counterbalanced projector frame extending through the open side of said frame, said projector frame having a pivotal mounting on said offset frame, substantially as described.

In testimony whereof I have hereunto set my hand.

HENRY E. HENRICKS.
